ROENTGEN TUBE WITH ANODE TURNING
ABOUT ITS LONGITUDINAL AXISKurt Schwarzer, Berlin, Germany; vested in
the Alien Property CustodianApplication September 27, 1940, Serial No. 358,686
In Germany October 14, 1939

4 Claims. (Cl. 250—148)

The invention relates to a novel Roentgen tube with anode turning about its longitudinal axis and equipped with two anodes, two cathodes and synchronous drive for both anodes so that, when the tube is directly connected to an alternating current-high tension, both half-cycles are utilized for the production of Roentgen rays originating at the same point of space. By the Roentgen tube according to the invention, the rectifier connections with four high tension incandescent cathode rectifiers, used up to the present in all high power Roentgen arrangements, become superfluous, so that the Roentgen arrangements become much simpler and cheaper.

The two anodes are preferably constructed as half rotary bodies of substantially similar shape and oppositely directed arranged rotatable in the same space portion with corresponding coordination of a cathode to each anode. A synchronous motor may be provided as drive for each anode. The drive may, however, be effected by one single synchronous motor, the two anodes being then connected the one with the other by a coupling piece possessing high insulating capability and heat constancy, for instance of quartz glass. Also in this coupling it is advisable to balance each anode alone relative to the turning axis in order to avoid too great mechanical stressing of the coupling piece.

A Roentgen tube according to the invention is shown by way of example partly diagrammatically in the accompanying drawings, in which

Fig. 1 shows a longitudinal section through the tube and

Fig. 2 is a top plan view on the anodes corresponding to the section line II—II in Fig. 1.

Figs. 3 and 4 show diagrammatic circuit connections, whereby the tube operates on both half-cycles of the alternating current.

Fig. 5 shows a second form of construction of the Roentgen tube, in which two motors are used.

In the high vacuum envelope 1 of the Roentgen tube, said envelope consisting preferably of glass, a bearing 2, 3 respectively is inserted at the two ends each with ball bearings, for the pivot axles, 4, 5 of the two anodes 6, 7. The anodes are coupled the one with the other by an insulating piece 8 made for instance of quartz glass. Each anode is balanced alone relatively to its turning axis by means of balancing bodies 9, 10. A motor making 3000 revolutions per minute (alternating current of 50 periods being supposed) is provided, the stator of this motor being designated by 11 and the rotor mounted on the turning axle 4

by 12. An incandescent cathode 13 is coordinated to the anode 6, the filament voltage being fed to said cathode through the intermediary of metal seals 14, 15 of the high vacuum envelope. The incandescent cathode 16 with the metal seals 17, 18 belongs to the anode 7.

When building up the Roentgen tube according to the invention the anode 6 and the incandescent cathode 16 in the one half-cycle have positive potential and the anode 7 and the incandescent cathode 13 have negative potential. In the other half-cycle the potential distribution is inverse. In the anode position shown in the drawings the incandescent cathode 16 is negative, the anode 7 positive and Roentgen rays are emitted from the tube to the left. In the next half-cycle the anode has turned by 180°, the incandescent cathode 13 is negative and the anode 6 positive, so that Roentgen rays are emitted from the same in the same direction. The position of the focal point in the space remains unchanged.

As shown in Figs. 3 and 4, the high tension for the Roentgen tube is supplied by the transformer 19, the filament voltage for the incandescent cathode 13 by the transformer 20 and the filament voltage for the incandescent cathode 16 by the transformer 21. The course of the circuit in the two half-cycles is indicated by arrows. The current flows in one of the half-cycles, as shown in Fig. 3, from the right hand end of the secondary winding of the high tension transformer 19 through the wire 22, the cathode 16, the anode 7 and the wire 23 to the other pole of the high tension transformer. In the next half-cycle the anodes have turned by 180°, as shown in Fig. 4. The current flows then from the left end of the secondary winding of the high tension transformer 19 through the wire 23, the cathode 13, the anode 6 and the wire 22 to the other pole of the high tension transformer.

Fig. 5 shows a second embodiment of the Roentgen tube according to the invention, in which for each anode a synchronous motor is provided as drive. In this instance it is evidently very material that both motors run accurately uniformly and synchronously with the operation voltage. The pivot axle 4 of the anode 6 is journaled in the bearings 2 and 24. The motor 12 is mounted on the axle 4 and rotated by the stator 11. The current is fed to the incandescent cathode 13 coordinated to the anode 6 by means of the metal seals 25, 26 of the high vacuum sleeve. The pivot axle 5 of the second anode 7 is journaled in the bearings 27, 28, and on this axle the rotor 29 is mounted which is rotated by the stator

30. The current is fed by the metal seals 17, 18 to the incandescent cathode 16, coordinated to this anode 7.

I claim:

1. Roentgen tube of the rotating anode type, comprising two anodes and two cathodes; the two anodes constructed as semi-rotary bodies of substantially similar form but oppositely directed and each cathode coordinated to each anode, a synchronous drive for both anodes, so that with direct connection of the tube to an alternating current high tension both semi-cycles are utilized for the production of Roentgen rays produced at the same point in the space.

2. Roentgen tube as specified in claim 1, comprising a synchronous motor for each anode as drive.

3. Roentgen tube as specified in claim 1, comprising a synchronous motor as drive for one of the anodes, and a coupling piece of high insulating power and heat constancy preferably of quartz glass and suitable for high vacuum connecting the second anode with the first anode.

4. Roentgen tube as specified in claim 1, in which each anode alone is balanced relative to its turning axis.

KURT SCHWARZER.
